UNITED STATES PATENT OFFICE.

EDWARD P. WELCH, OF GEORGETOWN, DISTRICT OF COLUMBIA, ASSIGNOR
TO HIMSELF, JAMES H. WELCH, ROSIA W. WELCH, HERBERT P. WELCH,
AND JAMES A. MALONEY, OF SAME PLACE.

IMPROVEMENT IN MIDDINGS-PURIFIERS.

Specification forming part of Letters Patent No. 135,953, dated February 18, 1873.

To all whom it may concern:

Be it known that I, EDWARD PRICE WELCH, of Georgetown, in the District of Columbia, have invented certain new and useful Improvements in Machinery for Purifying Middlings, of which the following is a specification:

My invention relates to that class of machinery for dressing flour in which a current of air is passed through screens to sift and separate the various qualities of flour, and a brush is used to clear the meshes of the screens.

The subject-matter of my improvement is hereinafter specified.

In the accompanying drawing, Figure 1 represents a vertical longitudinal section; and Fig. 2, a vertical transverse section through a middlings-purifier embracing my improvements.

The construction of the various parts of the machine being well understood by skillful constructors of milling-machinery, their details need not be particularly described here.

A screen, A, is suspended by radius links *a*, and vibrated by an eccentric, B, or other suitable means. Beneath this screen I mount a rotary brush, C, on an axis perpendicular to the face of the screen, and drive it by suitable belts or gearing, so that it may rotate across the face of the screen, which at the same time is vibrating across the brush, thus producing a diagonal drawing movement which I have found very effective in clearing the meshes of the screen from clogging matter. Any number of brushes desired may be used according to the requirements of the particular case. Instead of a simple brush rotating on its axis, roller-brushes might be mounted on horizontal axes in the brush-head, so as to have a compound rotating motion both on a vertical and a horizontal axis.

In addition to the brushes, I propose some-

times to use an air-pipe, D, extending longitudinally beneath the bolt with cross-pipes D' at suitable intervals. This pipe has numerous perforations to direct fine jets of air upon both the screen and brush, and clear them of obstructions. The brushes having long and flexible bristles, readily pass over the pipes which are interposed between the brush and screen.

The pipes may be extended around the sides and ends of the screen, so as to prevent the escape of the material or to arrest its rate of discharge at the tail end. This blast, it will be understood, is independent of the ordinary one passing upward through the screen, which is also used. The operation of my improved apparatus will readily be understood from the foregoing description.

I do not claim a vibrating screen with a blast passing through it; nor, broadly, the combination of a screen with a clearing-brush.

I claim as my invention—

1. The combination, in a middlings-purifier, of a vibrating screen through which a blast passes in one direction while the flour passes in the other, with a brush rotating across the face of the screen on an axis substantially perpendicular thereto, substantially as hereinbefore set forth, to produce a drawing action of the brush across the screen diagonal to its line of vibration.

2. The combination, in a middlings-purifier, of a vibrating screen, brushes rotating across the face of the screen, and a perforated air-pipe to direct streams of air upon the screen and brush, substantially as set forth.

In testimony whereof, I have hereunto subscribed my name.

EDWARD P. WELCH.
